(57) **ABSTRACT**

A modular, scalable sorting assembly for sorting items into boxes, comprising two sorting level units, each unit having accessible work spaces on both front and back sides, and with a work surface dividing each unit into upper and lower storage areas with through-slots formed into a lower storage area of each unit sized and shaped to store and receive one or more uniformly sized and shaped open top boxes. The upper storage area has a series of shelves sized and shaped to store items prior to sorting or after being sorted but prior to placement in the boxes. One of the two units is further comprised of a central workstation and a wing with a side wall configuration that angles the wing towards an area directly in front of the central workstation when the wing is positioned immediately adjacent thereto.

BACKGROUND OF THE INVENTION**Field of the Invention**

The present invention pertains to apparatuses used in the field of sorting numerous miscellaneous unsorted print and nonprint items in the form of books, magazines, LPs, cassettes, and compact discs. Specifically, the invention is a modular, scalable sorting assembly for efficient and systematic organization of relatively large quantities of print, and digital and analogue media items.

Background Art

Used books, magazines, and audio and/or visual media in the form of vinyl records, compact discs and VHS tapes are uniquely problematic for libraries and other entities collecting such items in order to resell them to others for fundraising purposes. Each used item must be manually identified by title, then organized into like groupings. The nature of used books and media is such that the items are all individualized, meaning they differ in subject matter, condition, price, age, and size and hence are neither easily nor practically sorted by automated sorting machines or systems. In relatively small quantities, such as less than a hundred items, used media are manually sorted by one or two individuals using existing software to scan and retrieve basic information about the item, including current pricing for the used item based on its identification, age and condition, and then the item is physically positioned in a designated box or pile of same or like items. If the item is going to be sold, the grouping may be for items of a same price (all items \$5 for instance), a same type of item (music

2

cds, or magazines, for instance), a same subject (history books, for instance), or any other type of useful grouping. This manual process is easily performed on a table, where like items are simply grouped together according to their desired groupings after each item is identified and sorted.

The problem with this manual process is that it is not easily or efficiently scalable to accommodate large volumes of media, such as when many hundreds or thousands of books, magazines, movie and music CDs, VHS tapes and vinyl records must be sorted and grouped. Manually sorting large volumes using known methods requires ample space and considerable physical labor. For a charity or other non-profit organization trying to hold a fundraiser, a used book and media sale with thousands, tens of thousands, and hundreds of thousands of used items can easily require a team of 30 or more people working several hours a day in a warehouse to sort the items for weeks. Worse, item sorting must be done prior to the sale, and typically this has resulted in all sorting being performed at the sale site, presenting logistical problems when the sale site lacks the space or manpower needed to sort the items, or when that space is required for other activities prior to the sale and cannot be cordoned off to allow the sorting to take place.

Additionally, used items are typically sold at a discounted price, and profit is difficult in circumstances where the organization lacks unpaid workers as the cost of paying workers to sort and group the used items may cost as much or more than the money that will be made by the sale of the sorted items. Hence, a used book and media sale often becomes a "rummage sale", where ungrouped and unsorted items are offered for sale and potential buyers must do the work of sorting and picking through the items. It is well known that presorting and presenting used books and other media for sale in organized and systematic ways increases sales, and hence the library or other entity holding the sale must carefully weigh the time and cost required to manually sort the items, and the desire to maximize sales.

What is needed is a sorting assembly that allows two or more people to systematically and efficiently sort and group large quantities of books and other physical media in a limited space.

What is also needed is a sorting assembly that is easily scalable to accommodate book and media volume and number of workers as needed.

What is also needed is a sorting assembly that is modular and transportable and thus easily adapted to any space as needed.

DISCLOSURE OF INVENTION

In a first aspect of the invention, a sorting assembly according to the invention is comprised of a first level sorting unit and a second level sorting unit. Either unit can be used alone to provide a single level of sorting, or more typically, the units are used together, along with a display unit and a storage unit after sorting is complete.

In a second aspect of the invention, the first level sorting unit features a doubled sided workstation with an upper shelving area for storage of sorted items, a work surface, and a series of slots sized and shaped to receive two boxes. A shelf for a computer is positioned centrally on each side of the first level sorting unit, with overhead lighting and power built into the unit. The second level sorting unit features a central station flanked by a pair of wing units angled to create a concave workstation such that a user standing in front of the central station can easily turn and access each wing efficiently. The second level sorting unit features upper

shelving for sorted items and lower shelving or through slots sized and shaped to receive the boxes used in the first level sorting unit. The second level unit, like the first level unit, is fully accessible from either side and thus both units must be positioned away from a wall to allow the user access to both sides.

In a third aspect of the invention, the first level sorting unit is comprised of a pair of opposed lower side walls having a first edge shape towards the front work side and a second edge shape towards the back work side, allowing the user to visually identify each side of the unit.

In a fourth aspect of the invention, the second level sorting unit is modular and additional central stations and wings can be added as desired.

In a fifth aspect of the invention, the sorting assembly components are wheeled, allowing the units to be easily moved to accommodate different room sizes and area where sorting is occurring. The modular nature of the assembly allows the user to quickly set up, sort, and demobilize the units. The storage and display units, also wheeled, allow the user to set up a display for a sale quickly and easily, as well as breakdown the sale equally quickly.

BRIEF DESCRIPTION OF THE DRAWINGS

The features and advantages of the invention will become apparent from a consideration of the subsequent detailed description presented in connection with accompanying drawings, in which:

FIG. 1 is a perspective view of a front side of a first level sorting unit (GAP unit) according to the invention.

FIG. 2 is a perspective view of a back side of the GAP unit in FIG. 1.

FIG. 3 is a back view of the GAP unit.

FIG. 4 is a side elevation view of the GAP unit.

FIG. 5 is a detail view of a through-slot of the GAP unit.

FIG. 6 is a second level sorting desk (SD unit), comprised of a pair of shelf wings on either side of a central workstation.

FIG. 7 is a front view of the central workstation of the SD unit.

FIG. 8 is a front view of one wing of the SD unit.

FIG. 9 is a back perspective view of the SD unit, shown with suggested locations for through-slots.

FIG. 10 is a sorting shelf unit for sorted item boxes.

FIG. 11 is a drawer-style shelving unit for sorted item boxes.

FIG. 12 is a detail view of a sorted item box for a drawer-style shelving unit.

FIG. 13 is a top view of the sorting assembly according to the invention.

DRAWINGS LIST OF REFERENCE NUMERALS

DETAILED DESCRIPTION

A sorting assembly according to the invention **100** is comprised of a first sorting unit or GAP unit **10** and a second sorting unit or SD unit **40**, the assembly **100** shown in a top view in FIG. 13, with its individual components shown in more detail in FIGS. 1-9, with storage and display assemblies according to the invention shown in FIGS. 10-12.

Items typically sorted by the sorting assembly **100** are print and digital media such as books, magazines, movie DVDs, CDs, LPs, comics, and cassettes providing a user multiple levels of sorting and the ability to quickly and efficiently sort items to a degree similar to what is found in a library or a bookstore, where books and other items are commonly grouped by subject, author, audience age, etc. The storage and display assemblies **60** **62** in FIGS. 9-12 allow the sorted items to be systematically stored, displayed and a sale set up and taken down quickly and easily.

Turning to the GAP unit **10** in FIGS. 1-5, the GAP unit **10** is a freestanding unit having a front side and a back side, an upper area and a lower area, the upper and lower areas separated by a front work surface **24a**. The GAP unit **10** is provided with wheels **10a** such as casters or other suitable wheels that allow the unit **10** to be moved as needed. The front side upper area is comprised of a plurality of shelves **18**, including a centrally located workstation shelf **12** for supporting a computer **14** or other equipment. One or more power outlets **12a** including USB and other useful ports are built directly into the GAP unit **10** to power lights **12b**, equipment and other electronics. The shelves **18** span at least 30% of a length measurement of the GAP unit **10**, and in the Figures is shown as being about $\frac{2}{3}$ of the length measurement. The shelves **18** are minimally at least 11 inches deep, which is a standard shelf depth. Shelves **18** can be configured to be deep enough to securely hold vinyl record sleeves, for instance, or other bulky items. The front work surface **24a** is sized and shaped to efficiently hold a plurality of sorted item boxes or boxes **22**.

In the Figures, the boxes **22** are uniformly sized and shaped, with a box length **24d**, a box width **24e**, and a box height **24f**. Boxes **22** shown in the Figures are rectangular in cross section i.e. cuboid, with the box length **24d** dimension

being larger than the box width **24e** however square boxes i.e. cubes, could be used in some applications where all 4 sides have a same dimension and the slot **34** size, front and back work surfaces, etc. adjusted accordingly. Side walls of the box **22** must be of a durable enough construction to support the box **22** and its contents **20** when positioned on the box length **24d**. The boxes **22** feature a lidless, open top and have a group designation **22a** on each box **22** and in the Figures, the group designation is shown as numbers but note that it could also be colors, words, or other ways of differentiating the boxes from one another. In contrast, an unsorted item box **20b**, holding unsorted items **20a**, are typically cardboard boxes or other boxes of varying sizes and materials used simply to collect the unsorted items.

The front work surface **24a** has a depth approximating one side of the box **22**, and a length sized to efficiently accommodate a plurality of immediately adjacent boxes **22**. The front work surface **24a** plus a height of the box **22** together approximate a same height as a standard kitchen countertop to provide a comfortable work surface height. In practice, the height of the box **22** is tall enough to accommodate a majority of common book sizes. Below the front work surface **24a**, the lower area is comprised of a series of vertically and horizontally adjacent through-slots or slots **34** sized and shaped to receive at least one and a maximum of two immediately adjacent boxes **22** positioned linearly within the slot **34**. Boxes **22** are stored in the slots **34** where they are accessible from the front and back sides of the GAP unit **10**.

The back side of the GAP unit mimics the front side, with an upper area featuring the plurality of sorting shelves **18** and an additional workstation **26** positioned centrally to allow items to be further sorted and processed. Note that the upper area of the back side of the GAP unit **10** can identically mimic the front side, and is designed for other equipment such as a printer (not shown) to be supported on the workstation shelf **12** for printing labels **26a**, invoices or other information relating to the sorted items. The back work surface **24b** is about 1 inch deeper than the width of the box **22** to allow secure positioning on the back work surface **24b**. The back work surface **24b** is also about 1 inch higher than the front work surface **24a**, with the back work surface **24b** taller so as to allow access to the uppermost wall of the box **22** sitting on the front work surface **24a** as shown in FIG. 4. The Figures show the back work surface **24b** having a raised central ledge portion **24c** with space directly beneath to accommodate the box **22**, drawer style.

Looking at FIG. 4, the GAP unit **10** is shown with a vertical upper side wall **30** supporting the plurality of sorting shelves **18** and a lower side wall **36** having an angled wall or edge **32** sloping downwards on the front side of the GAP unit **10**. The front work surface **24a** on the front side of the GAP unit **10** is lower relative to the height of the back work surface **24b** on the back side of the GAP unit **10** by about 8^{3/4} inches, slightly more than the height of the box **22**. This height difference is designed to ensure the user (not shown) has a same comfortable working surface height on either side of the GAP unit **10**. Note that all the approximate stated sizes in this disclosure are based on dimensions of a Buckhorn box, made by Buckhorn Inc, with a website at <https://buckhorninc.com>. The particular box used here is model SW241608, with the following dimensions 24" x 15" x 7". In the GAP unit **10**, the slots **34** are sized and shaped so as to position the Buckhorn box with its 24" side oriented so as to be parallel to a slot length, thus with a typical slot **34** using this box being about 48" long, between 15.5" to 16.5" wide and at least 7" tall. This particular Buckhorn box was used

during testing and is the basis for the dimensions of the separate units **10** **40** of the sorting assembly shown in the Figures and described herein. The angled wall **32** sloping along the front side of the GAP unit **10** allows the user to visually differentiate between front and back sides, and is one example of how the front and back sides can be easily identified. Alternatively, the lower side wall can have a same profile front and back, and each side labelled can be used to designate front and back, or different colors used, so long as visual differentiation is achieved. The inventor believes angling the side wall is an elegant design solution to identification.

Turning to FIGS. 6-12, the second sorting unit or SD unit **40** is shown as being comprised of a central workstation **42** having a front side with a work surface **50**, an optional drawer **52** for storing miscellaneous useful items such as writing utensils, a plurality of upper sorting shelves **42a**, and a plurality of lower sorting shelves **42b** for box **22** **20b** storage. In a typical configuration, the central workstation **42** is flanked on either side by a side wing workstation or wing **44** having sorted item shelves **42a** and lower shelves **42b** or slots **34** holding GAP sorted items **20** but instead of a work surface, each wing **44** is typically designed as storage of sorted items. When positioned together, the wings angle inwards to create an approximately concave station, its shape providing more efficient accessibility by the user standing at the central workstation **42** by minimizing travel of the user handling SD unit sorted items **20**. The inventor notes that more wings **44** and central workstations can be added, as needed, to more quickly sort items by accommodating more users. The SD unit **40** is configured like the GAP unit **10** to be accessible from both the front side and a back side. The sorting shelves **42a** are open on both the front and back sides of the SD unit **40** and temporarily store sorted items **20**. In embodiments where the lower shelves are in fact slots **34**, the boxes **20b** **22** can be stored or accessed from either side.

After sorting items with the SD unit **40**, the sorted items **20** are moved into boxes **22** and positioned immediately into the storage unit **62** for longer term storage, or into display units **60** ready for sale, as shown in FIGS. 10-12. The sorted items **20** in the display unit **60** are conveniently visible for sale purposes and easily removed when the sale is finished and the boxes **22** are stored in the storage unit **62**. The inventor notes that the display unit **60** is typically on wheels **10a** to allow easy moving of the unit **60**, and also that as an alternative embodiment, the display unit **60** may be a comprised of a wheeled base sized and shaped to receive a plurality of boxes **22** stacked on top of one another such that an open side of the box is positioned sideways to allow access to its contents. The storage unit **62** may be comprised of a plurality of drawer slots as shown in FIG. 11, or alternatively, be configured as long shelves with a depth compatible with the box **22** length to allow the boxes **22** to be accessed easily.

The boxes **22** used by the GAP unit **10**, SD unit **40**, display unit **60** and storage unit **62** are uniform in size and shape and have no lids. The boxes **22** shown in the Figures are stackable and strong, made of structural plastic and are similar to plastic milk crates. The inventor likes the Buckhorn box, but also believes any set of uniformly sized and shaped strong boxes can be used and the boxes shown are one size and shape that worked well during testing. For the embodiment where the boxes **22** themselves form the display unit **60**, opposed side of the boxes can be constructed with mating structures to allow the boxes to stack securely atop one another and allow fast build up and break down of

the units **60**. The inventor believes the boxes **22** could also be made of cardboard, such as banker's boxes or standard sized file boxes, however, he stresses that any box used must be strong enough to withstand the weight of the items and not crush or fall apart when sitting on its side in a display orientation as shown in FIG. 10. A plurality of boxes whose dimensions differ from those of the Buckhorn box would require modification of the sorting assembly's various units. From the inventor's perspective, no other type of box works as well as the Buckhorn box.

The GAP unit **10** and the SD unit **40** are designed to be used together to provide a minimum of two levels of sorting for the items and the type of sorting parameters used are selectable by the user. For instance, the GAP unit **10** as shown in the Figures is used to for a first level of sorting of items, such current market value. The SD unit **40** is then used to sort the first level sorted items using another grouping designation, for instance, reading level.

The inventor stresses that his sorting assembly **100**, minimally comprising the GAP unit **10** and the SD unit **40**, is shown in the Figures as sorting items **20** **20a** identified as books and other print type media. Items **20** **20a** include a wide variety of physical things, including toys, collectibles such as teacups, figurines and other things. The user is free to decide as to the type of grouping designations desired and use the GAP unit **10** and SD unit **40** accordingly. The inventor notes that it is possible to use just the GAP unit **10** or the SD unit **40** separately without the other however the use of both together provides superior sorting by allowing relatively small numbers of people (minimally two) to efficiently sort and process thousands of items using two-level sorting criteria in days rather than weeks, and then set up and tear down a book or other sale with the sorted items quickly with minimal effort and chaos. Sorting and organizing of items can thus be done offsite of the sale location, then quickly set up with the boxes **22** positioned in the display units **60**. Both the GAP unit **10** and the SD unit **40** enable a pair of users to work simultaneously at the same unit. The number of GAP units **10** and SD units **40** is increased to accommodate larger volumes of material to be sorted as well as number of users, hence the sorting assembly **100** is scalable. A single GAP unit **10** can for instance be paired with multiple SD units **40**, or vice versa, and the SD units **40** can include 3 or more wings or multiple central workstations and wings as needed. The sorted items **20** arranged in the display units **60** allows a bookseller or other seller to visually estimate sales with a simple glance at the number of empty boxes and their identifying groupings, such as price, type of item, etc. in a way that the currently used manual systems cannot so easily accomplish. The rolling units **10** **40** **60** **62** allow the user to sort items and set up or tear down a book or miscellaneous item sale in virtually any convenient location that is large enough to accommodate the sorting assembly, and to arrange the units as needed to accommodate the dimensions of the room as well as the needs of the users doing the sorting work.

It is to be understood that the above-described arrangements are only illustrative of the application of the principles of the present invention. Numerous modifications and alternative arrangements may be devised by those skilled in the art without departing from the scope of the present invention. For instance, the inventor notes that the modular nature of the sorting assembly **100** allows item sorting to be scaled up or down as needed, and thus any number of GAP units, or SD units and wings may be used together. The sorting assembly **100** shown in the Figures shows a basic or typical arrangement, but the modular nature of the assembly allows

for many variations. The inventor also notes that the computer shelf **12** does not need to hold a computer, but rather could be a touch screen display or other equipment, such as a printer, as needed for sorting items, or even a camera. The inventor uses his assembly for sorting books, vinyl records, magazines and other media, but it can be easily used to also sort toys, housewares, figurines, trading cards, and even clothing, and all within a same unsorted box. Hence, purchasing lots from estate sales are easily sorted using the assembly and the entire process of sorting, displaying, selling and removing the unsold items can be done easily and quickly on site or in another location. The inventor also believes that wheels on the units allow for easy arrangement and transport of the assembly, however the units could also be adapted to have feet suitable for sliding that would allow the units to be easily moved.

I claim:

1. A sorting assembly for use with a box having box width, a box length and a box height, with the box length having a length measurement greater than a width measurement of the box width, and an item to be sorted into the box, the sorting assembly comprising:

a first level sorting unit having a first unit front side, a first unit back side, and a first unit width;

wherein the first unit width is measured from a front edge of the first unit front side to a back edge of the first level back side;

a first unit left side and a first unit right side, and a first unit length;

wherein the first unit length is measured from the first unit left side to the first unit right side;

wherein each of the first unit front and back sides is further comprised of a first unit upper storage area and a first unit lower storage area separated by a first unit work surface;

wherein the first level sorting unit has at least two or more shelves on the upper storage area each spanning at least 30% of the first unit length;

wherein the first unit work surface is further comprised of a first unit work surface front side and a first unit work surface back side, the first unit work surface front side having a front surface length at least equal to the box width and a front surface width at least a same measurement as the box length;

wherein the first unit lower storage area is divided into at least two through-slots, each through-slot having a slot width and a slot height sized and shaped to receive the box width and box height, and a slot length equal to at least two box lengths, with a slot front opening accessible from the first unit front side, and a slot back opening accessible from the first unit back side; and a second level sorting unit having a central workstation with a side wall and an immediately adjacent wing, each of the central workstation and the wing having a second unit front side and back side, and a second unit work surface dividing each of the central workstation and the wing into a second unit upper storage area and a second unit lower storage area;

wherein each of the second unit lower storage areas of the central workstation and of the wing has at least one of a through-slot or shelf sized and shaped to receive the box;

wherein the second unit upper storage area is comprised of shelves sized and shaped to temporarily store items to be later placed in the box;

wherein the shelves of the second unit upper storage area are accessible from a front side and a back side of the central workstation and wing; and

wherein the first level sorting unit and the second level sorting unit each are further comprised of wheels along a floor facing side of each unit, whereby each unit is repositionable and moveable without further equipment.

2. The sorting assembly in claim 1, wherein the wing and central workstation unit are separate units.

3. The sorting assembly in claim 1, further comprising a second wing positioned on an opposed side of the central workstation whereby the second level sorting unit has a concave tripartite structure.

4. The sorting assembly in claim 1, wherein the wing has an extended side wall sized and shaped to be positioned immediately adjacent the side wall of the central workstation so as to position the second unit front side of the wing towards a user standing in front of second unit front side of the central workstation, whereby lateral movement of the user is minimized in order to move the item from the central workstation to the wing.

5. The sorting assembly in claim 1, wherein the first unit upper storage area is further comprised of at least one of a computer workstation shelf and a power source.

6. The sorting assembly in claim 1, further comprised of an integral light source positioned in the first unit upper storage area.

7. The first level sorting unit in claim 1, further comprising a pair of opposed walls vertically positioned at the first unit left and right sides of the first unit lower storage area, each wall of the pair of opposed walls having a front facing top wall and a back facing top wall;

wherein the front facing top wall has at least one of a different shape and color than the back facing top wall,

whereby the front facing and back facing walls of the first unit left and right sides are visually differentiated.

8. The first level sorting unit in claim 7, wherein the front facing top wall is angled downwards about 45 degrees from a horizontal plane extending from the back facing top wall, the horizontal plane being parallel to a ground surface.

9. The sorting assembly in claim 1, further comprising a display unit having at least two shelves sized and shaped to receive and store at least two boxes positioned adjacently on the shelves so that their box openings face sideways towards an open accessible side of each shelf, and further comprising wheels affixed to a floor-facing side of the unit, whereby the unit is repositionable.

10. The sorting assembly in claim 1, further comprising a storage unit having a plurality of through-slots, each through-slot sized and shaped to receive at least one box.

11. The sorting assembly in claim 1, wherein the first unit back side is further comprised of a raised centralized work area having a slot sized and shaped to receive and store one box accessible from one side of the slot.

12. The sorting assembly in claim 1, wherein the first unit lower storage area is further comprised of a shelf sized and shaped to receive at least one of the box and at least one container having a size and shape different from that of the box.

13. The sorting assembly in claim 1, wherein the second unit upper storage area has an uppermost shelf having an open top side.

14. The sorting assembly in claim 1, wherein the second unit lower storage area of the central workstation has at least one shelf sized and shaped to receive and store at least one secondary box.
